UNITED STATES PATENT OFFICE.

MORRIS M. STONE, OF NEW YORK, N. Y.

GARMENT-HANGER.

SPECIFICATION forming part of Letters Patent No. 752,122, dated February 16, 1904.

Application filed September 21, 1903. Serial No. 174,100. (No model.)

To all whom it may concern:

Be it known that I, MORRIS M. STONE, a citizen of the United States, and resident of the city, county, and State of New York, have invented certain new and useful Improvements in Garment-Hangers, of which the following is a full, clear, and exact specification.

My invention relates to a combined coat, vest, and trousers hanger, and has for its object to produce a practical article of this kind simple in construction and inexpensive in manufacture.

In the accompanying drawings, forming part of my application, and in which like letters of reference denote like parts throughout, Fig. 1 is an end elevation of my improved holder, and Fig. 2 is a front elevation of the same.

Referring to the drawings, the letter A indicates a curved bar, preferably of wood, which serves as a support for the coat or the coat and vest, if desired, and B indicates a strand of wire twisted upon itself. This wire is so twisted that eyes or openings b are formed 20 therein at intervals, through which the bar A may be passed. C is a hook or ring at the upper end of the strand, and D a cross-piece at its lower terminus. From each end of the cross-piece D clasps E are suspended. These 30 clasps in this form of the invention consist of

spring members e, having a tendency to press from each other, but being held together by a ring or similar device f. The bar A may be placed through any of the eyes b, thus determining the distance of the bar from the 35 cross-piece D.

In employing my invention an entire suit of clothes may be neatly and compactly suspended from one hanger. The coat may be placed over the bar A, the waistcoat either 40 over the bar A or cross-piece D, and each of the trousers bottoms may be inserted between the jaws of the clasps secured to the cross-piece.

Having now described my invention, what I claim as new, and desire to secure by Letters 45 Patent, is—

A garment-hanger comprising the combination of a curved bar, a second bar consisting of a strand of wire twisted upon itself and having eyes formed therein through which 50 the curved bar may pass, a cross-piece suspended from the lower part of said second bar, and a clasp depending from each end of said cross-piece, substantially as described.

In witness whereof I have hereunto set my 55 hand in presence of two witnesses.

MORRIS M. STONE.
